UNITED STATES PATENT OFFICE.

JAMES GIBBINS, OF SPRINGFIELD, MASSACHUSETTS.

DESIGN FOR AN INKSTAND.

SPECIFICATION forming part of Design No. 13,948, dated May 29, 1883.

Application filed December 22, 1882. Term of patent 14 years.

To all whom it may concern:

Be it known that I, JAMES GIBBINS, a citizen of the Dominion of Canada, residing at Springfield, in the county of Hampden and State of Massachusetts, have invented and produced a new and original Design for Inkstands, of which the following is a specification, reference being had to the accompanying drawing, forming a part thereof.

10 The figure is a side view of my newly-designed inkstand.

My design consists of the figure or representation of an elephant standing and holding in its proboscis a cup, 2, which is to hold or contain the ink, into which a pen may be dipped. This figure or image 1 of the elephant may be made of metal and solid, in

which case the cup 2 may be refilled with ink, as occasion requires; or the figure or image 1 and cup 2 may be made hollow and of glass 20 or other suitable material, with a small conduit extending through the proboscis and opening into the cup, so that by pouring ink into the body through a suitable opening the ink may flow through the proboscis into the 25 cup held therein.

I claim—

The design for an inkstand, consisting of the image of an elephant holding in its proboscis a cup to contain the ink.

JAMES GIBBINS.
